Atty.

UNITED STATES PATENT OFFICE.

EDGAR F. HATHAWAY, OF WELLESLEY, MASSACHUSETTS, ASSIGNOR TO SHAWMUT ENGINEERING COMPANY, OF BOSTON, MASSACHUSETTS, A CORPORATION OF MASSACHUSETTS.

SPOOL-RETARDING MEANS FOR TUFT FRAMES.

Application filed January 29, 1923. Serial No. 615,580.

To all whom it may concern:

Be it known that I, EDGAR F. HATHAWAY, a citizen of the United States, and resident of Wellesley, in the county of Norfolk and 5 State of Massachusetts, have invented certain new and useful Improvements in Spool-Retarding Means for Tuft Frames, of which the following is a specification.

This invention relates to tuft frames such 10 as are used in weaving tuft fabrics of the character of Axminster carpets and the like, and is intended to provide a simple and effective means for securing the desired retardation of the yarn spool as it rotates in 15 the tuft frame to permit the unwinding of the yarn therefrom in order to deliver the pile-forming tufts to the fabric in the weaving operation.

Generally speaking the improvement 20 consists in providing a properly mounted movable brake member combined with a spring arranged to yieldingly press said brake member into frictional engagement with the rotatable spool in order to retard the same 25 and create the proper drag on the yarn as it is unwound from the spool for use. Provision is also made for securing any desired degree of adjustment to secure the requisite degree of retardation or braking action, and 30 in order to protect the spring and adjusting means from interfering with or catching the yarn provision is also made whereby the spring and its adjusting member may be located inside the hollow carrier bar forming 35 the backbone of the tuft frame. These and other features of the invention will be explained in the following specification and will be defined in the claims hereto annexed.

In the accompanying drawings I have illustrated several forms of construction and arrangement embodying the principles of this 40 invention, in which:

Figure 1 is a front elevation of the end portion of the spool-carrying tuft frame.

Figure 2 is an end elevation of the same 45 viewed from the inside with the hollow carrier bar shown in cross section.

Figure 3 is a front elevation partly in section showing a modified form of brake construction.

Figure 4 is an endwise view of the same

viewed from the inside showing the carrier bar in cross section.

Figures 5 and 6 are views similar to Figures 3 and 4 showing another modified construction and arrangement.

The carrier bar 1, the suspension brake 2, with the chain-engaging hook arm 3, and the spool-supporting bearing lug 4 in which is mounted the journal of the spool 5, are 60 shown embodying the same construction of different forms of the invention and form no part of the present improvement.

In the practice of my invention, according to the form shown in Figures 1 and 2, 65 I provide a brake lever 8, which intermediate of its ends as at 9, is pivoted to the tuft frame, in this case directly opposite to the suspension brake 2.

At its spool-engaging end the brake arm 70 of the lever is preferably provided with a friction pad or shoe 10 which may be made of rawhide, fibre or any suitable material. The power arm 11 of the brake lever is angularly disposed in relation to the working arm so as to extend across the front 75 face of the carrier bar 1, and is perforated to receive a headed bolt 12 which is passed through an aperture 13 in the face of the hollow carrier bar, and carries at its screw 80 threaded end an adjustable nut 14 which is accessible through the aperture 15 in the opposite face of the hollow carrier bar and which receives the thrust of a helical spring 16 so as to exert a yielding pull upon the arm 11, whereby the brake arm of the lever is yieldingly pressed into frictional engagement with the periphery of the spool 5, the pad 10 being, to all intents and purposes, a 85 part of the brake arm.

In order to adjust the tension of the brake member against the spool the thrust member 14 may be turned in either direction by a screw-driver or other tool either to further compress the spring or to allow it to 95 expand; hence any desired degree of braking pressure may be brought to bear upon the spool, while at the same time the spring and the adjustable thrust member, being located inside the hollow carrier bar, are 100 protected against entanglement with the tuft yarn passing from the spool to the usual

individual tuft tubes (not herein shown as they are well known and form no part of the present invention).

In the form of the improvement shown in Figures 3 and 4 an angular spring lever 17 is provided whose brake arm or working member is provided with a friction shoe or pad 36 and whose power arm 17^a, angularly disposed to the working arm, is located inside of the hollow carrier bar, the intermediate or fulcral portion of the lever being formed into one or more pivotal eyes 18 which surround a fulcral pin 19 mounted just inside an aperture 20 formed in the top of the carrier bar, preferably a little beyond the attaching arms 6 and 7 of the suspension arm, thereby avoiding perforating of both the carrier bar and either of its attaching members for the passage and free working of the lever.

An adjusting screw 21 passes through the suspension arm 2 where it closes the end of the hollow carrier bar and carries a thrust member in the form of a nut 22 to which one end of the helical spring 23 is attached, the other end of the spring being connected with the power arm 17^a of the brake lever. The contractile tension of the spring serves to press the brake pad into frictional engagement with the periphery of the spool. This pressure will be varied according to the position of adjustment of thrust member 22.

The form of the invention shown in Figs. 5 and 6, employs a movable spring-pressed brake member whose movement is in straight line instead of in a circular arc.

In this form the carrier bar has opposite perforations located in the plane of the spool head and in substantially radial relationship thereto. It comprises a hollow spring casting or plunger 25, on which is preferably mounted a friction pad 26 and is slotted along one side to receive the laterally projecting guide lug or pin 28 of a thrust nut 27 which is adjustably held at any desired position according to the adjustment of the adjusting screw 29 by the relatively stiff supporting spring 30. The brake tensioning spring 31 will exert a frictional pressure between the movable brake member 25, 26 which will vary according to the position of the thrust member or nut 27. The spring 30 serves to keep the head of the adjusting screw always seated against the bottom wall of the carrier bar and is therefore stiffer than the spring 31.

The form shown in Figs. 3-6 have one advantage over that shown in Figs. 1 and 2, since there is at all times substantially the same area of frictional contact between the brake and the spool, as the pads wear, due to the fact that in both said forms the movement of the pads are in a plane longitudinal or axial of the spool.

An important feature characterizing all forms of the invention consists in an arrangement which permits the use of a comparatively rigid or inflexible brake member in association with some form of tensioning spring, thereby avoiding the weakening and uncertainty of action of brakes characterized by flexible spring arms which are easily distorted in use.

What I claim is:

1. In a tube frame for tuft weaving, the combination with a tubular carrier bar for externally supporting a series of tuft tubes, a yarn spool rotatably supported lengthwise of said carrier-bar, a movable brake member arranged to press against a peripheral portion of said spool, a brake-actuating spring mounted inside said tubular bar and operatively combined with said brake to force the brake yieldingly against the spool, a tensioning screw projecting through an aperture formed in an enclosing wall of said carrier-bar for connection with said interior spring and acting, by its adjustment, to vary the pressure of the brake against the spool, substantially as described.

2. In a tube frame for tuft weaving, the combination of a hollow carrier-bar, a yarn-spool rotatably mounted thereon, a pivotal brake arm arranged to swing between the spool rim and the top of the carrier-bar, a brake-actuating spring located inside the carrier bar and operatively combined with the brake to cause the brake to yieldingly press against the spool rim, substantially as described.

3. In a tuft frame for weaving pile fabrics, the combination with a supporting frame and its rotatable yarn spool, of a brake arm pivoted intermediately of its ends to the spool-supporting frame to swing it into braking engagement with said spool, and means for causing said brake arm to normally press against the spool in order to retard rotation thereof, substantially as described.

4. In a tuft frame for weaving pile fabrics, the combination with a supporting frame and its rotatable yarn spool, of a brake lever pivoted intermediately of its ends with one arm disposed to normally press against said spool to exert frictional retardation thereon, and a spring arranged to press against the other arm of said lever to maintain such frictional retardation, substantially as described.

5. In a tube frame for tuft weaving, the combination with a carrier-bar and its rotatable yarn spool, of a movable brake member arranged to frictionally engage a head of the yarn-spool to retard rotation of the spool, an actuating spring combined with said brake member to cause the brake member to yieldingly press against the spool head, a spring-engaging threaded nut and

an adjusting screw therefor, said nut being adjustable by means of said screw to vary the position of the nut, thereby varying the pressure of the spring-actuated brake 5 against the yarn-spool.

6. In a tuft frame for weaving, the combination of a hollow carrier bar and its suspension bracket secured thereto, a rotatable yarn spool, a movable brake member arranged to frictionally engage said yarn spool, a tensioning spring arranged to yieldingly press the brake member into frictional engagement with said spool, and an adjustable thrust member by which the frictional 10 pressure is varied and an adjusting screw having threaded engagement with said

thrust member and projecting through a wall of the carrier-bar, said spring and said thrust member being mounted inside the carrier bar, substantially as described. 20

7. In a tuft tube frame for weaving, the combination of a longitudinal carrier bar and its associated yarn spool, of a movable brake member of substantially rigid material and a separate spring arranged to yieldingly press said rigid brake member into retarding contact against a portion of the spool, substantially as described. 25

In witness whereof, I have subscribed the above specification.

EDGAR F. HATHAWAY.
